UNITED STATES PATENT OFFICE.

AUGUST G. TRAUTMAN, OF BROOKLYN, NEW YORK.

SPARK-PLUG.

1,328,932.

Specification of Letters Patent.

Patented Dec. 2, 1919.

Application filed June 26, 1917. Serial No. 177,155.

To all whom it may concern:

Be it known that I, AUGUST G. TRAUTMAN, a citizen of the United States, residing at Brooklyn, in the county of Kings and State 5 of New York, have invented new and useful Improvements in Spark-Plugs, of which the following is a specification.

This invention is a spark plug wherein a supplementary spark gap and condenser are 10 employed to increase the efficiency of the spark gap disposed within the cylinder.

One object of the invention is to provide a spark plug with two gaps arranged in series.

15 Another object is to provide a spark plug with a condenser which when assembled will form a unitary structure with the plug.

A further object is to provide a spark plug formed of readily separable sections, one of 20 which is provided on its exterior surface with a wire gauze shell which opens to the outside atmosphere whereby a certain portion of air can be taken in to mix with the spark as the latter is produced and which 25 also serves as a guard to prevent accidental ignition of gases about the engine which might otherwise be ignited if the outer spark gap is exposed.

A still further object is to provide a spark 30 gap with a condenser operatively connected to the electrode to produce a higher voltage and therefrom a more efficient spark to be formed between the electrode of the main gap to insure a prompt firing of the explosive mixture of the cylinder.

Broadly stated, the invention comprises a shell through which extends an electrode surrounded by insulating material, which insulating material is provided intermediate 40 of the ends with a shouldered portion and a chambered portion adjacent one end and near said latter end with sight or peek holes, said electrode terminating within said chambered portion, and lock nut adapted to 45 operate with the shell and with the shouldered portion of the insulating material to firmly hold said electrode in its operative position within the shell, a condenser operatively connected to said lock nut, a wire 50 gauze section extending upward from and connected to said condenser and to cap or crown serving as a cover for said plug and

an electrode projecting through said cap, one end of which terminates adjacent the end of the first mentioned electrode extending from the shell to coöperate with the lower end of the central or main electrode passing through the center of the plug. The several component parts of the plug being formed to permit them to be readily separated from each other also to permit the assembly plug to be inserted in the cylinder of an internal combustion engine.

One practical form of construction and assembly will be described and illustrated in 65 the accompanying drawings, in which—

Figure 1 is a side elevation of the plug.

Fig. 2 is a vertical sectional view, and

Fig. 3 is an enlarged sectional view of the upper half of the plug.

The shell of the plug generally indicated by the numeral 5 may be formed with any suitable material having the usual external threads 6 to engage with threads formed in the cylinder of an internal combustion engine. Passing through the central portion of the shell 5 is a hole or passage 7. The lower end of the shell 5 preferably slopes from the threads 6 to the passage 7, which sloping portion is indicated at 8. Adjacent 80 the upper end of this shell 5, the shoulder or flange section 9 is formed which extends outwardly from the threads 6, the under surface of this flange may form a seat with the exterior wall of the cylinder and thus provide a gas tight joint. This flange 9 is provided internally with an aperture upon 85 which are formed threads 10.

Disposed to surround the upper end of the hole or passage 7, is a chamber or shouldered 90 portion 11 which joins to a flat shouldered section 12 and terminates adjacent one end of the threads 10.

A lock nut is provided which has a threaded portion 15 to coöperate with the threads 95 10 formed on the shoulder 9. Adjacent the threaded portion 13 is a flange 14 which is adapted to seat against the upper side of the flange 9 and extending upwardly from the flange 14 is a threaded portion having the 100 threads 15 formed thereon.

As shown in Figs. 2 and 3, the upper and lower surfaces of this lock nut which may be generally indicated at 16 are preferably flat

so that the under flat surface will engage and seat upon the shouldered portion 12 of the shell 5.

Disposed above the lock nut 16 is an insulating section 17 which may have disposed within its interior a condenser. This section 17 is provided with a flanged portion 18 which has formed thereon threads 19, which threads are adapted to coöperate with the threads 15 formed upon the upper portion of the lock nut 16, the lock nut 16 is provided with a center hole or passage 20 and the insulating section 17 is also provided with a center hole 21. The insulating section 17 may if desired be provided with an upwardly extending collar or sleeve 22 which may be formed of wire gauze shown more particularly in Figs. 2 and 3.

If desired the condenser instead of being mounted within the insulating section 17 may be disposed above such insulating section within the collar or sleeve, 22.

Adapted to coöperate with the upper end of the wire gauze 22 is a cap or crown piece 23 which may serve as a cover for the chamber formed within the collar or sleeve. Suitable means may be provided for the coöperative engagement of the wire gauze 22 and the cap 23. Disposed centrally of the cap 23 is a threaded aperture generally indicated at 24. Adapted to pass this aperture is a threaded stem 25, the threads of which are indicated at 26. This stem 25 may be provided with a slot end 27 and to coöperatively engage with the threads 26 are the nuts 28 and 29, which serve to hold the stem 25 at any desired point relative to its passing through the threaded aperture formed in the cap 23. The lower end of the stem 25 is preferably provided with a flange or shouldered section 30 which serves to engage with the under side of the cap 23. By means of the slot end 27 when the nuts 28 and 29 are loosened, the stem 25 may be adjusted in and out of the cap 23, for such adjustment the nuts 28 and 29 may be so turned as to lock the stem 25 in its adjusted position.

Projecting from the stem 25 and the flange 30 is an electrode 31 which may be formed of the usual material such as "meteor wire" commonly employed for spark plugs.

Disposed to be positioned within the hole 33 or passage 7, the shouldered portion 11 of the shell, the hole or aperture 20 of the lock-nut 16, the hole 21 of the insulating section 17 is a porcelain body 32. This porcelain body is provided with a through passage 33 through which passes the electrode 34. The lower end of the electrode 34 projects outwardly from the flat faces 35 formed on the lower end of this porcelain body 32.

As shown more particularly in Fig. 2, there is a shouldered portion or flange indi-

cated at 36 which serves to abut against the flat face 35. The sparking end of this electrode 34 is indicated at 37 and extends downwardly from the shoulder or flange portion 36.

The upper end of the porcelain body 32 is preferably provided with a chambered section generally indicated by the letter A. Intermediate of the length of this chamber A there may be provided a series of openings 38 which may serve as sight or peek holes. The upper end of this porcelain body 32 is adapted to abut and engage with the under surface of the cover 23. The electrode 31 projects within the chamber A and the electrode 34 also projects a sufficient distance to provide a spark gap in connection with the electrode 31. The upper end of the electrode 34 is provided with a shouldered portion or flange 39 which is adapted to seat against the body 32 and at the bottom of the chamber A.

Thus it will be seen that the electrode 34 is firmly held in the through passage 33 of the porcelain body 32 and its upper end projecting above the shouldered portion or flange 39 forms a sparking electrode 40 as shown more particularly in Fig. 2. The shell 5 is also provided with an electrode indicated at 41 which is shown as being secured to one side projecting outwardly and inwardly so that this through end indicated at 42 is adjacent the sparking end 36, of the electrode 34. The gap formed between the electrodes 42 and 37 is of the width commonly employed.

From the construction and assembly shown and described the spark plug is provided with two gaps, a main one and a secondary one. The secondary one being employed to determine whether or not the main gap is sparking. This will be known as the two gaps are placed in series.

By the employment of the condenser the spark may be increased in efficiency as the condenser will be charged upon the completion of the circuit and discharged at the moment of breaking.

What is claimed as new is:—

1. A spark plug comprising a shell, an insulating body extending through and beyond the shell, a lock nut engaging one end of the shell and securing the insulating body against movement in the shell, an insulating ring having threaded coöperation with the lock nut, a reticulated casing secured to and rising from the insulating ring, the insulating body extending lengthwise said casing and formed with a condenser chamber, an electrode extending from a point within said chamber to the terminal of the body, and a second electrode extending within the chamber and terminating with such relation to the first electrode as to form a spark gap within the chamber.

2. A spark plug comprising a shell, an insulating body extending through the shell, a reticulated casing surrounding the extended portion of the body, a lock nut engaging the shell and securing the body against movement therein, an insulating ring engaging the lock nut and supporting and fixing the casing, said body being formed with a chamber in that portion
- 5 within the length of the casing and with 10 openings in the casing walls, and electrodes extending lengthwise the body and spaced within the chamber and opposite the openings to form a spark gap.
- In testimony whereof I affix my signature.

AUGUST G. TRAUTMAN.
